CLAIM

The ornamental design for a gun safe, as shown and described.

DESCRIPTION

FIG. 1 is a perspective view of a gun safe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is another perspective view thereof, with the door in an opened position; and,

FIG. 9 is another perspective view thereof, with the door dismounted.

The broken lines shown in the figures are for the purpose of illustrating portions of the gun safe and form no part of the claimed design.

1 Claim, 9 Drawing Sheets
